Des. 221,109
Patented July 6, 1971

221,109

OTOSCOPE

Helmut A. Heine, Herrsching, Upper Bavaria, Germany,
assignor to Optotechnik G.m.b.H., and Propper Manufacturing Company, Inc.

Filed June 12, 1970, Ser. No. 23,464

Term of patent 14 years

Int. Cl. D24—02; D16—08

U.S. Cl. D57—1

FIG. 1

FIG. 2

FIG. 3

FIG. 4

FIG. 5

FIG. 6

FIG. 1 is a top plan view of an otoscope in accordance with my new design;

FIG. 2 is a front elevational view thereof;

FIG. 3 is a side elevational view thereof;

FIG. 4 is a rear elevational view thereof;

FIG. 5 is a view similar to FIG. 3 showing the opposite thereof; and

FIG. 6 is a bottom plan view thereof.

I claim:

The ornamental design for an otoscope, as shown.
